WEFT DETECTOR FOR BOX LOOMS

Application filed April 17, 1931. Serial No. 530,910.

This invention relates to improvements in weft detector mechanism for shifting box looms and it is the general object of the invention to provide improved means for moving a single feeler into operative position with respect to the shuttle which is to become active.

In a loom operating with a pair of shifting shuttle boxes at each end and two shuttles each active but one pick at a time it is desirable to effect a change in the loom operation when the weft of the active shuttle is exhausted. In such a loom there is always an idle shuttle and an active shuttle. It is an important object of my present invention to provide a means for moving the feeler from one to the other of the shuttle boxes by an indication given by and dependent upon the position of the boxes to be related to the shuttle about to become active.

The boxes ordinarily shift with respect to the lay when the latter is in the forward part of its stroke, and it is desirable that the feeler move with the selected box during this period. It is an important object of my present invention to accomplish this result by providing means a part of which are set by the shifting of the boxes so that prior to the next period of box shift the detector will be moved to a new position. I find it convenient to accomplish this result by means of a lever or the like which changes its position with respect to fixed paths of movement of two lay carried actuators, the latter being effective during the backward movement of the lay at a time when the boxes are away from the detector to shift the position of the latter with regard to a positioner or carrier which it self moves with the boxes.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a side elevation of a portion of a loom having my invention applied thereto, the shifting shuttle boxes which are on the

left hand side of the loom being shown in section,

Fig. 2 is a top plan view of a portion of the mechanism shown in Fig. 1,

Fig. 3 is a perspective view showing the oscillating lever and its actuators, and

Figs. 4 and 5 are diagrammatic views illustrating certain operations of the mechanism.

Referring to Figs. 1 and 2, I have shown a loom frame 10 and a lay 11 mounted on a sword 12 which moves about a rocker shaft 13 by mechanism not shown but well understood. A shuttle box structure 14 is movable vertically with respect to the lay by a box lifter rod 15 which may be operated in any approved manner, as by a link 16 connected to any form of box motion, so that either the upper box 17 or the lower box 18 may be operatively positioned with respect to the shuttle race 19. This means that either the upper shuttle S or the lower shuttle S' may be active, depending upon the demands of the pattern.

The weft detector, which is shown for illustrative purposes as of the side slip type, comprises a feeler arm 20 having a weft engaging tip 21 and is supported by a detector frame 22. The detector is pivoted as at 23 to a slide 24, and these moving parts are held yieldingly in rearward position by means of a light compression spring 25 located in the casing 22 and bearing against the arm 20. Suitable stops may be provided to limit both angular and longitudinal movements of the detector in a manner similar to that set forth in prior patent to Payne No. 1,738,198.

When sufficient weft *w* is present the slide 24 will move forwardly and the detector will be held against substantial angular movement. When exhaustion is present, however, the slide may remain at rest and the detector will swing around its pivot 23 to cause the arm 20 to engage an indicating wire 26. The latter is pivotally mounted in a small bearing frame 27 and is held by means of a light tension spring 28 in normal position against the detector arm 20. Angular movement of the detector will swing the wire 26 against the action of spring 28 in a clockwise direction as viewed in Fig. 2. Such motion will result in

a longitudinal movement to the right of a controller 29 attached to the wire 26.

The matter thus far described forms no part of my present invention, the detector enclosing the weft of one or another of the 5 shuttles during forward beating of the lay when a shuttle is in position to coact with the detector.

My present invention relates to means for 10 positioning the detector with respect to the shuttle becoming active, and in carrying my invention into effect I mount the detector casing on a bracket 40 which is provided at its lower end with a hub 41 having sliding 15 engagement with respect to a vertical rod 42. The latter is also mounted for sliding movement, being guided by fixed upper and lower guide bearings 43 and 44, respectively.

An arm 45 is secured by means of screw 46 20 to the lower end of the rod 42 and has a slot 47 therein to receive a lifting pin 48 carried by the collar 49. The latter is secured to the box lifter rod 15 and moves vertically with the latter. From the mechanism 25 thus far described it will be seen that the boxes and rod 42 rise and fall together.

A lever supporting arm 50 has a hub 51 which is secured by means of screw 52 in adjusted vertical position on rod 42. Secured to 30 the arm is a stud 53 on which is pivotally mounted a three-arm lever 54. The latter has a substantially horizontal arm 55 slotted as at 56 to receive a pin 57 secured to the hub 41. The lever also has upper and lower arms 35 58 and 59, respectively, the latter being connected to a spring 60 the upper end of which is attached as at 61 to an extension on the arm 50. The spring acts as a yielding lock 40 to hold the lever 54 in either of two positions to which it may be moved by mechanism to be described.

Secured to the under side of the lay is a bracket 65 to which is adjustably secured an upper actuator pin 66 movable in slot 67 and 45 also a similar lower actuator pin 68 adjustable in slot 69. The bracket is held to the lay by means of a nut 70 so that the actuator pin 66 and 68 move back and forth with the lay through fixed paths.

50 In describing the operation of the detector it will be assumed that the shuttle boxes are in their raised position, the weft detector opposite the upper box, and the lay in its rear-most position, this condition being represented diagrammatically in Fig. 4. Rod 42 was previously raised by engagement of the lever 54 with upper pin 66, the lever having been thus thrown in a counter-clockwise direction, thereby raising the detector. This 55 result was accomplished during the backward movement of the lay during the pick immediately preceding that represented by the position shown in Fig. 4. As the lay reaches approximately its mid-position when moving 60 forwardly the shuttle boxes will start to move

downward, so that rod 42, collar 43, and lever 54 will all descend, thereby requiring downward movement of the detector with the upper box as the latter descends to active position. During this downward movement 70 of the boxes the lay moves forwardly, and then after having passed front center starts to move rearwardly. When it reaches approximately top center, or mid-position between front and rear extreme positions, the 75 top shuttle will be picked out of the upper box. If exhaustion be present in this shuttle the detector will indicate so that a change will be brought about in the operation of the loom when the upper shuttle reaches the 80 opposite side.

As the boxes come to rest the lever 54 reaches its low position with the arm 55 raised, but at this time the lower arm 59 will lie in the path of the rearwardly moving bottom pin 68 and as the lay nears the end of its backward movement the last named pin will engage the lever arm and move the latter in a right hand direction around its pivot. The effect of this movement is to lower the hub 41 by means of the pin and slot connection 85 which the latter has with the lever 54, thus depressing the detector so that the latter is opposite the bottom shuttle, being positioned 90 by engagement of the hub 41 with the collar 51. As the boxes rise on the succeeding pick 95 the detector will be opposite the lower shuttle, or the one which is moving into action, and if exhaustion exists therein a change in the operation of the loom will be 100 called for by the feeler.

From the foregoing it will be seen that I have provided simple means for changing the position of the detector with respect to the shuttle boxes during that part of the cycle of 105

the loom when the shuttle boxes are away from the detector. More specifically, this result is accomplished every pick of the loom by the use of a part which alternates from one to the other of two extreme positions by a force 110 derived from the lay. The detector and the parts which control its position may be considered as having two distinct movements, the first of which is a selecting movement which determines the point from which the detector 115 shall start its second or detecting movement. During the selecting movements the detector 54 and the stand 40, which are geared together, move with respect to the box lifter rod 120 and the positioning rod 42, but after the selection has been completed, these parts move with the boxes without substantial relative vertical movement.

Having thus described my invention it will be seen that changes and modifications may 125 be made therein by those skilled in the art without departing from the spirit and scope of the invention and I do not wish to be limited to the details herein disclosed, but what I claim is:

1. Weft detecting mechanism for a loom having a lay and two shuttle boxes thereon which shift one toward and the other from active position every pick of the loom, a single feeler to be positioned to cooperate with either shuttle box, and a controller for the feeler operative every pick of the loom by a motion derived from the lay to position the detector to cooperate with the shuttle box moving toward active position.

2. Weft detecting mechanism for a loom having a lay and two shuttle boxes thereon which shift one toward and the other from active position every pick of the loom, a single feeler to be positioned to cooperate with either shuttle box, means operative by a force derived from the lay to position the detector every pick of the loom in cooperative relation with respect to the shuttle box moving into action, and a connection between the means and boxes to move the feeler with the boxes as they shift.

3. Weft detecting mechanism for a loom having a lay and two shuttle boxes thereon which shift one toward and the other from active position every pick of the loom, a single feeler to be positioned to cooperate with either shuttle box, a train of geared mechanism including an oscillatable element and a support for the feeler, and means dependent upon shifting movement of the boxes and movement of the lay to move said train to place the feeler cooperatively with respect to the box moving toward active position.

4. Weft detecting mechanism for a loom having a lay and two shuttle boxes thereon which shift one toward and the other from active position, a single feeler to be positioned to cooperate with either shuttle box, a train of geared mechanism including an oscillatable element and a support for the feeler, and means dependent upon shifting movement of the boxes and movement of the lay to move said train every pick of the loom to place the feeler cooperatively with respect to the box moving toward active position.

5. Weft detecting mechanism for a loom having a lay and two shuttle boxes thereon which shift one toward and the other from active position every pick of the loom, a single feeler to be positioned to cooperate with either shuttle box, a pair of regularly moving actuators on the lay, an oscillatable element movable with the shuttle boxes to be related to one or the other of said actuators at a time, and connections between the oscillatable element and the detector to position the latter cooperatively with respect to the shuttle box moving into active position.

6. Weft detecting mechanism for a loom having a lay and two shuttle boxes thereon which shift one toward and the other from active position every pick of the loom, a single feeler to be positioned to cooperate with either shuttle box, weft detecting mechanism

for a loom having two shuttle boxes, a single feeler to be positioned to cooperate with either shuttle box, a pair of regularly moving actuators, and an oscillatable member movable with the shuttle boxes into engaging position with respect to one or the other of the actuators depending upon the position of the shuttle boxes, and connections between the oscillatable member and the feeler to position the latter cooperatively with respect to the shuttle box to become active on the next pick of the loom.

7. Weft detecting mechanism for a loom having a lay and two shuttle boxes thereon which shift one toward and the other from active position every pick of the loom, a single feeler to be positioned to cooperate with either shuttle box, weft detecting mechanism for a loom having two shuttle boxes, a single feeler to be positioned to cooperate with either shuttle box, a pair of regularly moving actuators, a lever movable about an axis which shifts with the shuttle boxes, said lever having one arm to engage one of the actuators and another arm to engage the other actuator, there being but one arm in engaging position with its actuator at a time, and connections between the lever and the feeler to position the latter by a force derived from one or another of the actuators depending upon the position of the shuttle box, in cooperative relation with respect to the shuttle box next to be active.

8. In weft detecting mechanism for a loom having a lay and a pair of shifting shuttle boxes each movable to active position, a box lifter rod to position the boxes, a single feeler, a feeler lifter rod movable with the box lifter rod, a support for the feeler movable to either of two positions relatively to the feeler lifter rod, an element moving with the feeler lifter rod and connected to the support and movable in two directions, and means to move the element in one direction when the boxes are in one position and said means to move the element in the other direction when the boxes are in the other position, the element and support when in either position being movable to the other position as the boxes shift to cause movement of the latter with the feeler.

In testimony whereof I have hereunto affixed my signature.

SAMUEL A. NELSON.
